Primary Examiner — Mark Goodwin(74) *Attorney, Agent, or Firm* — Greenblum & Bernstein, P.L.C.(57) **CLAIM**

The ornamental design for a cabin for a working vehicle, as shown and described.

DESCRIPTION

FIG. 1 is a front elevational view of a cabin for a working vehicle, showing our new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a perspective view thereof; and,

FIG. 8 is another perspective view thereof.

The cabin for a working vehicle according to the present invention is a cabin mainly used for a working vehicle such as a tractor or a combine.
